C. A. SCHROYER.
CAR DOOR FASTENER.
APPLICATION FILED DEC. 12, 1910.

1,226,706.

Patented May 22, 1917.

UNITED STATES PATENT OFFICE.

CHARLES A. SCHROYER, OF OAK PARK, ILLINOIS, ASSIGNOR TO Q. & H. COMPANY, OF CHICAGO, ILLINOIS, A CORPORATION OF MAINE.

CAR-DOOR FASTENER.

1,226,706.

Specification of Letters Patent. Patented May 22, 1917.

Application filed December 12, 1910. Serial No. 596,861.

To all whom it may concern:

Be it known that I, CHARLES A. SCHROYER, a citizen of the United States, and a resident of the village of Oak Park, county of Cook, 5 and State of Illinois, have invented certain new and useful Improvements in Car-Door Fasteners, of which I do declare the following to be a full, clear, and exact description, reference being had to the accompanying 10 drawing, forming part of this specification.

The present invention seeks to provide an improved fastener for the sliding doors of railway freight cars. Ordinarily, a sliding door is suspended from a track arranged 15 above and at one side of the door way, guides being provided for the lower edge of the door and which guides hold the door in vertical position and against the outer face of the door frame when the door is closed. 20 In accordance with the present invention, improved fastening means are provided in connection with the guides for holding the door in closed position with the lower portion thereof within the door opening. The 25 invention consists in the features of improvement hereinafter set forth, illustrated in the preferred form in the accompanying drawings and more particularly pointed out in the appended claims.

30 Figure 1 is a view in side elevation showing a portion of the side of a car having my improved door fastener mechanism applied thereto. Fig. 2 is a view upon an enlarged scale on line 2—2 of Fig. 1. Fig. 3 is a detail front view of the lower corner of the door and adjacent portion of the car wall. Fig. 4 is a view in vertical section on line 35 4—4 of Fig. 3, but showing the locking bolt in the position indicated by dotted lines in 40 Fig. 3.

The side wall A of the car is provided with a suitable door way or opening having posts B at opposite sides thereof. The posts B are provided with shoulders within the 45 opening which are preferably tapered or inclined downwardly and inwardly so that the door can be held in closed position by the improved fastening devices with the lower portion thereof within the door opening. 50 The sliding door D may be of any suitable construction. That shown comprises a frame d having a sheet metal covering d'. The sliding door is hung in front of the door in any suitable manner which will permit this lower edge being held within the

door opening when in closed position. In the construction shown, hangers E at the upper edge of the door are provided with rollers e which engage a Z-shaped track bar C that is fastened to the side of the car above 60 the door opening and extends over the door and into spaces e' in the hangers. When the door is opened and closed it moves in front of the door posts B, the movement being guided by L-shaped guide brackets K secured, as usual to the side of the car. In accordance with the present invention, improved fastening means is provided in connection with the guide brackets K for holding the door in closed position with the 65 lower portion thereof within the door opening and between the door posts B. In the preferred form shown, the fastening means comprises locking bolts H mounted upon the lower portion of the door. 70

For this purpose the lower portion of the door D is provided with attached brackets G that are conveniently fixed to the door by bolts g and g'. One of the bolts g' serves as a pivot for a locking bolt H. The upper 75 end of each locking bolt H is formed with a slot h through which the pivot bolt g' passes, so that the locking bolt H can not only swing on the pivot bolt g', but also can be raised bodily for a purpose to be presently explained. Each of the locking bolts H, in the preferred form of the invention, is formed with an expanded lower portion h' and with an outwardly extending part or tongue h² that is adapted to fit within a 80 seat k formed in the upstanding portions k' of the L-shaped guide brackets K K. To close the door, it will be moved laterally in 85 front of the doorway until the edge of the door contacts with the stop or plate F. As 90 the door is thus moved, the lower edge of the door will travel inside the upstanding portions k' of the brackets K and as the locking bolts H strike these brackets they will be swung to one side, the locking bolt H at 95 the left-hand end of the door D passing easily over the bracket K. When the door D is thus brought directly opposite the door opening, the attendant will lift or slide upward the locking bolts H and at the same 100 time will push or swing inward the lower portion of the door until the inner face of the door bears against the shoulders of the door posts B, and the locking bolts H will 105 then be released so as to cause their expanded 110

lower ends h' to pass inside the upstanding portions h' of the brackets K K and to cause the tongues or projections h^2 to rest within the seats h of the brackets.

It is manifest that when the door is thus brought to closed position, the locking bolts H, coöperating with the brackets K, will securely hold the door in such position; and at such time the lower portion of the door 10 D will be within the door opening, while its upper portion will extend outside such opening.

When the door is to be opened, the attendant will lift the bolts H and swing them 15 to one side of the brackets K K, so that the lower portion of the door will easily move outward to the vertical position indicated in Fig. 4, when it may be slid to one side of the doorway.

It is manifest that the details of construction above set out may be varied within wide limits without departing from the scope of the invention as defined in the appended claims.

Having thus described my invention, what I claim as new, and desire to secure by Letters Patent, is:—

1. In fasteners for railway car doors, the combination with a car having a door opening and posts on opposite sides of said opening and a sliding door therefor, of L-shaped guide brackets for the lower edge of the door, said guide brackets being fixed to the car and having upturned flanges arranged 30 to overlap the outer face of the car door, and locking devices arranged to fit between the upturned flanges of said brackets and the outer face of the door to hold the lower portion of the latter, in closed position, within 35 the door opening and between said posts, substantially as described.

2. In fasteners for railway car doors, the combination with a car having a door opening and posts on opposite sides of said opening and a sliding door therefor, of L-shaped 45 guide brackets for the lower portion of the door, said brackets being fixed to the car and having upturned flanges arranged to overlap the outer face of the car door, and locking bolts mounted on the outer face 50 of the door near its lower edge, said locking bolts having slotted upper ends, pivot bolts extending through said slotted upper ends for connecting said locking bolts to the door, and said locking bolts having enlarged lower 55 ends arranged to fit between the upturned flanges of said guide brackets and the outer face of the door to hold the lower portion of the door, in closed position, within the door opening and between said posts, substantially 60 as described.

3. In fasteners for railway car doors, the combination with a car having a door opening and a sliding door therefor, of L-shaped 65 guide brackets for the lower edge of the door fixed to the car and having upturned flanges arranged to overlap the outer face of the car door, and pivoted, vertically movable locking bolts mounted on the outer face 70 of the door near its lower end and arranged to fit within said guide brackets to hold the lower portion of the door within the door opening in closed position, said locking bolts having outwardly projecting lugs and the outer, upturned flanges of said brackets having 75 seats for said lugs, substantially as described.

CHARLES A. SCHROYER.
